UNITED STATES PATENT OFFICE.

MORTON J. VOGEL AND JACOB B. GRINOCH, OF NEW YORK, N. Y.

SPEED-CONTROLLED CIRCUIT CLOSER.

Application filed September 23, 1924. Serial No. 739,286.

This invention relates generally to speed limit signal devices intended more particularly for application to automobiles to give a signal when a certain speed is exceeded by the automobile, thereby ensuring against inadvertent exceeding of any selected maximum speed.

The invention has for an object the provision of a novel and simple device of this sort which may be readily set to operate at any desired speed.

For further comprehension of the invention, and of the objects and advantages thereof, reference will be had to the following description and accompanying drawing, and to the appended claims in which the various novel features of the invention are more particularly set forth.

Fig. 1 of the drawing is a face view showing my improved speed limit signal device combined with a speedometer.

Fig. 2 is a front view of the device with the casing removed from the adjustment shaft being shown in transverse section.

Fig. 3 is a transverse vertical sectional view taken on the line 3—3 of Fig. 2.

Fig. 4 is a horizontal sectional view taken on the line 4—4 of Fig. 2.

Fig. 5 is a detail vertical sectional view taken on the line 5—5 of Fig. 3 and illustrating more particularly the construction of the lock.

In the drawing the reference numeral 10 indicates the ordinary main frame bracket 5 of a combined speedometer and odometer. On this bracket is mounted the usual oscillatory speed indicating drum 12 having suitable numbers on its perimeter, and the usual mileage indicating wheels or drums 13 also 40 having suitable numbers on their perimeters, these parts being adapted for operation by a flexible shaft, not shown, that is connected to one of the wheels in the ordinary manner. Fixed co-axially to the drum 12, and 45 extending radially over the top end thereof, is a finger 15, which, as will be apparent, oscillates as the speed of the automobile varies, this finger serving as the medium through which electrical contact is made 50 with an adjustable element to close the circuit to the signal when the given speed is attained or exceeded.

Fixed to the frame 10 and electrically insulated therefrom as at 18, is an upwardly 55 extending yoke-shaped bracket 19, which is here shown as formed by the angular legs

19' that are attached at their upper ends to opposite sides of a bearing block 19^a, being secured to the latter by a bolt 20. This bracket 19 might be constructed of a single casting if desired. The bracket 19 is formed on its lower end with outturned feet 21 that rest on the frame 10 and are secured to the latter by screws 22 taking through suitable apertures in the said feet and screwed into threaded sockets in the frame. The bearing block 19^a has mounted therein a horizontal shaft 23 that extends from front to rear of the device and has a bevel gear 24 fixed to its rear or inner end, the opposite, or front, 70 end of the shaft extending through the front of the face plate or casing element 25 that supports the frame 10.

The gear 24 meshes with a ring-gear 27 that is supported by the bearing block 19^a 75 and has fixed thereto, and projecting downwardly therefrom, a finger 28 that has a horizontally projected lower end portion 28', this lower end portion extending radially inward. Suitably journaled in the block 19^a, 80 co-axially of the gear 27, and projecting downward from the bottom face of the block, is a spindle 30 to which is fixed an arm 31 having a downturned end portion 31' that normally rests against the inturned end portion 28' of the finger 28, being retained in such position by means of a light spring 32, such as the hair spring of a watch, that is attached at one end to the block 19^a and at 85 its other end to the said spindle 30. The 90 downturned end portion 31' of the arm 31 extends into the path of movement of the finger 15 attached to the speed indicating drum 12.

To permit of the finger 28 being locked 95 in any desired adjusted position the outer end of the shaft 23 is rigidly attached to an enlarged head 35 that is rotatably mounted in a barrel or cylinder 36 fixed to the casing element 25. In the head 35 are a number of 100 apertures 37 that extend parallel to the axis of the shaft 23. In these apertures are slidably mounted the plunger pins 38 that have outturned inner ends 39. These inner ends engage in notches or serrations 40 in 105 one radial wall of a recess 41 formed in the barrel 36, being retained in this position by means of an expansion spring 42 coiled around the shaft 23 and bearing on the inner ends of the pins. The other radial wall 110 of the recess is likewise formed with serrations or notches 43 complementary to the

serrations 40, the two walls being spaced apart just sufficient distance to allow the members 39 to move therebetween. When a suitable key is inserted in the apertures 37 5 the end elements 39 of the pins 38 are moved into registry with the space between the two series of serrations or notches in the recess 41, permitting the head 35, and with it the shaft 23, to be rotated to adjust the finger 10 28. The cylinder 36 is formed with a disk-like flange 45 that may have a series of numbers marked thereon, while the head 35 is formed with a projecting pointer 46 adapted to be brought into registry with a selected 15 one of these numbers, the parts being so arranged that the arm 15 engages the part 31' and so closes the circuit to a signal element when the speed reaches the point to which the pointer is set.

20 The signal means may comprise both a bell 50 and a light which receive current from a battery 52. The feed wires 53 and 54 are grounded respectively to the frame 10 and the bracket 19 which, as above pointed 25 out, are insulated from one another, and it will be obvious that when the parts 15 and 31' contact with one another the circuit through the signals will be closed.

Having thus described my invention, what 30 I claim as new and desire to protect by Letters Patent of the United States is as follows:—

1. In a device of the class described having an oscillatory speed indicating drum 35 with a contact finger mounted thereon, the combination of a frame mounted above said drum, a bearing block supported by said frame, a horizontal shaft rotatable in said bearing block, a bevel gear fixed on one end 40 of said shaft, another bevel gear rotatably supported, and meshing with said bevel gear, a downwardly projecting finger depending from said latter bevel gear, a spindle co-axially supported in said latter bevel gear, a 45 contact arm fixed to the lower end of said spindle, said contact arm being in the path of motion of said contact finger, a spring co-acting between said spindle and latter men-

tioned bevel gear, normally urging said contact arm to abut against said downwardly 50 projecting finger, and means for locking said horizontal shaft in angularly adjusted positions.

2. In a device of the class described having an oscillatory speed indicating drum with a 55 contact finger mounted thereon, the combination of a frame mounted above said drum, a bearing block supported by said frame, a horizontal shaft rotatable in said bearing block, a bevel gear fixed on one end 60 of said shaft, another bevel gear rotatably supported, and meshing with said bevel gear, a downwardly projecting finger depending from said latter bevel gear, a spindle co-axially supported in said latter bevel gear, a 65 contact arm fixed to the lower end of said spindle, said contact arm being in the path of motion of said contact finger, a spring co-acting between said spindle and latter mentioned bevel gear, normally urging said contact arm to abut against said downwardly 70 projecting finger, means for locking said horizontal shaft in angularly adjusted positions, and means for indicating the relative 75 adjusted positions of said horizontal shaft, said locking means and indicating means being connected with the end of said shaft remote from the attached bevel gear.

3. In a device of the class described, having an oscillatory speed indicating drum 80 with a contact finger mounted thereon, and an angularly adjustable gear mounted above said drum, the combination of a downwardly projecting finger depending from said gear, a spindle co-axially supported in said gear, a 85 contact arm fixed to the lower end of said spindle, said contact arm being in the path of motion of said contact finger, and a spring co-acting between said spindle and gear, normally urging said contact arm to abut 90 against said downwardly projecting finger.

In testimony whereof we have affixed our signatures.

MORTON J. VOGEL.
JACOB B. GRINOCH.
